US0D1112927S

(12) **United States Design Patent** (10) Patent No.: **US D1,112,927 S**
(45) Date of Patent: ** Feb. 10, 2026

(54) **HAIR TOOL**

(71) Applicant: **Kirby Beauty LLC**, Encino, CA (US)

(72) Inventors: **Erik Berg Kreider**, Brooklyn, NY (US); **Celestine Knowles**, Los Angeles, CA (US); **Matthew Spencer**, Brooklyn, NY (US); **Aiden Lee**, Queens, NY (US); **Hanbi Ko**, New York, NY (US); **Yubin Lee**, Jersey City, NJ (US)

(73) Assignee: **Kirby Beauty LLC**, Encino, CA (US)

(**) Term: **15 Years**

(21) Appl. No.: **29/941,636**

(22) Filed: **May 10, 2024**

(51) LOC (15) Cl. **28-03**

(52) U.S. Cl.

USPC **D28/30**

(58) Field of Classification Search

USPC D28/7, 20-34; D30/158, 159

(57) **CLAIM**

The ornamental design for a hair tool, as shown and described.

DESCRIPTION

FIG. 1 is a front left perspective view of a hair tool, showing our new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The broken lines shown in the drawings illustrate portions of the hair tool that form no part of the claimed design.

1 Claim, 5 Drawing Sheets
